UNITED STATES PATENT OFFICE.

WILLIAM F. KRICHBAUM, OF NEWARK, NEW JERSEY, ASSIGNOR TO FOSTER ENGINEERING COMPANY, A CORPORATION OF NEW JERSEY.

AUTOMATIC BOILER-FEED REGULATOR.

1,075,043.

Specification of Letters Patent.

Patented Oct. 7, 1913.

Application filed August 5, 1911. Serial No. 642,489.

To all whom it may concern:

Be it known that I, WILLIAM F. KRICHBAUM, a citizen of the United States, residing at Newark, in the county of Essex and State of New Jersey, have invented certain Improvements in Automatic Boiler-Feed Regulators, of which the following is a specification.

This invention relates more particularly to that class of automatic boiler feed regulators which operate thermostatically or by the expansion and contraction of a tube into which steam is admitted by the fall of water level in the boiler and from which it is excluded by the rise of the water, thus maintaining the water at uniform height in said boiler.

The objects of the invention are to provide such an automatic feed regulator which shall be very compact in form; to obtain a mechanism which shall avoid in its construction the employment of delicate or unreliable devices and arrangements, such as pilot valves, diaphragms, floats, springs, internal working parts and the like; to obtain a simple, strong construction, which shall be efficient in its working; to provide such a regulator which can be readily and easily attached to a boiler, and to secure other advantages and results as may be brought out in the following description.

In the accompanying drawings in which like numerals of reference indicate the same parts throughout the several figures, Figure 1 is a general view of my invention applied to a typical boiler; Fig. 2 is a side elevation of the regulator alone; Fig. 3 is a rear view of the same; Fig. 4 is a central vertical longitudinal section taken through the upper cap and connections of the expansion tube, and Fig. 5 is a like section taken through the lower cap and connection of said tube to the boiler, and through the valve which said expansion tube governs or regulates.

In said drawings, 1 indicates a tube made from any metal having a high coefficient of expansion. The lower end of this tube, which stands in substantially vertical position, is threaded into a base 2, and said base preferably has a substantially horizontal extension 3 by which it is mounted upon the valve 4 which governs the flow of water through the feed pipe 5 to the boiler 6. In said base 2, and leading from the seat for the lower end of the expansion tube 1, is a

hole or passage 7, and preferably said hole or passage opens through a boss 8 adapted to be connected, as by coupling and piping 9, 10, to the water column 11 of the boiler at a low point thereof, or to the drain pipe 12 of said water column, so as to drain the expansion tube 1. The upper end of said expansion tube is threaded to screw into a cap 13, suitably provided with an outlet 14 adapted to be connected, as by piping 15, 65 with the said water column 11 at that point of the height thereof at which it is desired for the water level to stand. I have shown this point as at the middle gage, for purposes of illustration, but obviously it might 70 be higher or lower, if desired. Upon the opposite sides of said cap 13 are laterally projecting arms 16, 16 each carrying a vertical or substantially vertical slideway or sleeve 17 adapted to slidably receive a guide 75 rod 18. The said guide rods 18, 18 are securely fastened in the base 2, or lateral ears 19 thereof, and project upwardly parallel with one another and with the expansion tube, being connected at their upper ends by 80 the yoke 20 at a point above the cap 13. From said yoke 20 a tongue 21 projects outwardly and downwardly in the same general direction as the base extension 3 and above the same, and provides a fulcrum for a bell-crank lever 22, the power or short substantially horizontal arm 23 of which rests on an adjustable stud 24 in the top of the cap 13 of the expansion tube. Said stud preferably is threaded for its lower end portion 90 to screw into a socket 25 tapped in the top of the cap, a lock nut 26 serving to hold it fast when adjusted, and at its top the stud has an angular head 27 for turning, ending in a pointed tip 28 above said head. 95

The work arm 29 of the bell crank 22 is long and projects downward adjacent to the expansion tube 1. At its lower end said long arm is pivotally attached to the power arm 30 of another bell crank 31 which is pivoted, as at 32, to a forked yoke 33 adjustably attached to the guide rods, 18, 18 by means of the split collars 34, 34. The work arm 35 of said second bell crank 31 works in a slot 36 in the stem of the above mentioned valve 100 4, the outer end of said arm being properly weighted, as at 37, to normally seat said valve.

The operation of the device is as follows: Normally, the water in the boiler or water 110

column 11 covers and seals the end of the pipe 15 leading to the top of the expansion tube 1, so that steam is excluded therefrom and the tube is cool or contracted. In this 5 condition of the expansion tube, the long arm 29 of the bell crank lever 22 is free to swing outward from the expansion tube and allow the weight 37 to depress the arm 35 of the lower bell crank 31, so as to slide the 10 valve proper of the valve 4 downward into closed position, as shown in Fig. 5. This prevents water from entering the boiler through the feed pipe 5. When the water gets low in the boiler, it uncovers the opening 15 of the pipe 15 into the water column 11 and steam enters through said pipe 15 into the expansion tube 1, heating the same. Said tube 1 expands as it is heated, carrying its top cap 13 upward with the sleeve 20 17 sliding upon the rods 18, thus pressing upward against the short arm 23 of the bell crank lever 22 and swinging the long arm 29 inward at its lower end or toward the expansion tube in the drawings. This swings 25 the lower bell crank lever 31 so as to raise the weight 37 and draw the valve proper of the valve 4 upward to open the same. Such opening of the valve 4 permits water to flow through the feed pipe 5 into the boiler 6 and 30 obviously the flow continues until the steam is again shut off from the expansion tube 1 and said tube contracts sufficiently to close the valve 4.

Having thus described the invention, what 35 I claim is:

1. In a boiler feed regulator, the combination of a base adapted to be secured to the boiler feed valve, an expansion tube projecting upward from said base, guide rods 40 at opposite sides of said expansion tube, a cap for said expansion tube having arms slidably engaging said guide rods, a yoke connecting said guide rods above said cap, a bell-crank lever fulcrumed on said yoke with 45 one arm extending between the guide rods transversely of the end of the expansion tube and adjacent thereto the other arm of the bell-crank projecting downward longitudinally of the expansion tube, a second yoke 50 on said guide rods near the base, a second bell-crank fulcrumed on said yoke with one arm connected to said downwardly projecting arm of the first-mentioned bell-crank, and means for connecting the other arm of 55 the second bell-crank to the boiler feed valve to open and close the same as the expansion tube varies in length.

2. In a boiler feed regulator, the combination of a base adapted to be secured to the 60 boiler feed valve, an expansion tube projecting upward from said base, guide rods at opposite sides of said expansion tube, a cap for said expansion tube having arms slidably engaging said guide rods, a yoke connecting said guide rods above said cap, a 65

bell-crank lever fulcrumed on said yoke with one arm extending between the guide rods transversely of the end of the expansion tube and adjacent thereto the other arm of the bell-crank projecting downward longitudinally of the expansion tube, a second bell-crank fulcrumed in fixed relation to the base adjacent thereto with one arm connected to the first-mentioned bell-crank, and means for connecting the other arm of the second bell-crank to the boiler feed valve to open and close the same as the expansion tube varies in length. 70 75

3. In a boiler feed regulator, the combination of a base adapted to be secured to the boiler feed valve, an expansion tube projecting upward from said base, guide rods at opposite sides of said expansion tube, a cap for said expansion tube having arms slidably engaging said guide rods, a yoke connecting said guide rods above said cap, a bell-crank lever pivoted to said yoke with one arm extending between the guide rods transversely of the end of the expansion tube and adjacent thereto the other arm of the bell-crank projecting downward longitudinally of the expansion tube, and means for connecting said last-mentioned arm of the bell-crank to the boiler for the valve to open and close the same as the expansion tube varies in length. 80 85 90

4. In a boiler feed regulator, the combination of a base, an expansion tube projecting upward from said base, guide rods at opposite sides of said expansion tube, a cap for the expansion tube slidably engaging said guide rods, a bell-crank lever pivotally connected to said guide rods with one arm extending transversely of the end of the expansion tube adjacent thereto and the other arm projecting downward longitudinally of the expansion tube, and means for connecting said last-mentioned arm of the lever to the boiler feed valve to open and close the same as the expansion tube varies in length. 100 105 110

5. In a boiler feed regulator, the combination with an expansion tube, and means for connecting said tube to a boiler at the normal water level therein, of a bell-crank lever having one arm extending transversely of said tube adjacent its end, a stud connected to said end of the expansion tube and adapted to be adjusted longitudinally of said tube by rotation, said stud having an extremity rotatably engaging the arm of the bell-crank lever so as to permit adjustment of the stud, means for connecting the other arm of the bell-crank lever to the boiler feed valve to open and close the same as the expansion tube varies in length, and means for supporting said parts. 115 120

6. In a boiler feed regulator, the combination with an expansion tube and means for connecting said tube to a boiler at the normal water-level therein, of a base providing 125 130

a socket for said tube, a drain tube extending downward from said socket, rods extending from said base longitudinally of said tube at opposite sides thereof, a closing 5 cap on said tube having sleeves receiving said rods a yoke connecting the ends of said rods and having a tongue projecting laterally from the line of the tube, a bell crank lever fulcrumed on said tongue with a short 10 arm extending across the said cap of said expansion tube and a long arm extending longitudinally of the tube, and means for connecting the end of said long arm to the boiler feed valve to open and close the same 15 as the tube varies in length.

7. In a boiler feed regulator, the combination with a boiler feed pipe having a valve therein, of a base mounted on said feed pipe, an expansion tube seated in said base and 20 connected to the boiler at normal water-level therein, a drain for said expansion tube leading from said base, rods extending from said base longitudinally of said expansion tube on opposite sides thereof, a yoke connecting 25 said rods and having a tongue projecting laterally from the line of the tube of the first class, a bell crank lever fulcrumed on said tongue with a short arm extending across the end of the expansion tube 30 and a long arm extending longitudinally thereof toward the base, a second bell crank lever mounted on one edge of said base beneath the said tongue with one arm connected to said long arm and its other arm 35 connected to the stem of the feed valve.

8. In a boiler feed regulator, the combination with a boiler feed pipe and a valve therein, of a base having an extension se-

cured to said valve and supporting the base, an expansion tube seated in said base and 40 connected to the boiler at normal water-level therein, a drain for said expansion tube, a support on the base for said expansion tube, a bell-crank lever fulcrumed on said support with a short arm extending 45 over the end of said tube and a long arm extending longitudinally of said tube adjacent thereto, and means for connecting the lower end of said long arm to said valve to open and close the same as the expansion 50 tube expands and contracts.

9. In a boiler feed regulator, the combination with an open-ended expansion tube, a feed pipe leading to said boiler, and a valve in said feed pipe, of a base fixed on said 55 valve and having a socket for said expansion tube, a drain leading from said socket, rods extending upward from said base piece at opposite sides of said tube, a yoke connecting said rods above said tube, a bell-crank lever fulcrumed on said yoke with a short arm extending over the expansion tube and a long arm extending downward adjacent to said tube, a cap for the upper end of the expansion tube having 60 65 means for connection to the boiler, adjustable means on said cap adapted to engage said short arm, a lower bell-crank having one arm connected to said long arm of the upper bell-crank and its other arm engaging the valve stem, and a weight normally holding said valve closed.
